SPARK PLUG

Edward B. Nowosielski, Bloomfield, N. J., assignor to Eclipse Aviation Corporation, East Orange, N. J., a corporation of New Jersey

Application February 5, 1936, Serial No. 62,524

12 Claims. (Cl. 123—169)

This invention relates to spark plugs, and particularly to an improved spark plug having a novel self-shielding construction facilitating the maintenance of proper temperature conditions and the avoidance of deterioration resulting from either too much or too little heat at any of the points along the path of current flow.

An object of the invention is to provide a spark plug of the type described wherein the 10 sparking point may be kept within a suitable temperature range and excessive heat rapidly dissipated. In this connection a feature of the invention is the provision of air circulating means in two distinct regions in the plug assembly, one 15 of which regions of air circulation operates to supplement the other and, in conjunction therewith, achieve the stated objective.

Another object of the invention is to provide an improved method of shielding and insulating the high tension circuit of a spark plug, as well as a novel structural combination 20 of parts adapted to cooperate in the attainment of improved shielding and insulating properties.

For example, I provide, for application to a 25 shielding element of the mica sleeve lined type, an improved method of protecting the mica lining, as well as a novel construction of adjacent parts to eliminate the possibility of fraying at the edges of the mica, notwithstanding repeated withdrawals and re-insertions of the connecting cable.

The improved insulating properties are due, in large measure, to the choice of insulating 30 materials of different composition for use in the different regions of the plug assembly where different conditions are encountered; and in this respect the construction differs radically from that of the all-mica or all-porcelain plugs of the prior art.

In the embodiment shown I use three different 35 materials to answer the different requirements resulting from the different conditions to be met.

The three materials chosen, by way of example, are mica, Bakelite and porcelain—mica as the material to line the radiating tube portion of the outer shield, Bakelite as the material to protect both the mica lining and the rubber-covered ignition cable, and porcelain as a material 50 which is superior to stacked mica as the instrumentality to withstand the persistent flash-over tendencies existing along the surfaces of the center electrode spindle and lower shell.

These and other objects will appear more fully 55 in the detailed description of the invention which

follows. Although only one embodiment of the present invention is illustrated in the accompanying drawing, it is to be expressly understood that this drawing is for the purpose of illustration only and is not to be construed as a limitation 5 of the scope of the invention, reference being had for this purpose to the appended claims.

In the drawing:

Fig. 1 is a longitudinal sectional view of a 10 device embodying the invention; and

Fig. 2 is a transverse end, or bottom plan view.

Referring first to Fig. 1, the apertured shielding element 10 is shown as an upward extension of the cylinder engaging base or shell 11, there being an intermediate polygonal portion 12 which 15 receives a wrench or other tool for insertion of the plug in the cylinder wall. The lower portion of the element 10 is also shown as provided with a polygonal section 13 facilitating its attachment to the shell 11, but it is to be understood that the 20 two members 10 and 11 may be integral if preferred.

In the space within the element 10, there is 25 a cooling and ventilating chamber surrounding a long thin metallic jacket 15 lined with a tube 16 of rolled mica constituting the wall of a second annular chamber closed at its upper end by a non-conducting spacer tube 17 having a metallic skirt 18 adapted to engage the mica lining 16 of jacket 15 and thus facilitate transfer 30 of heat from the center electrode spindle 14 to the outer surface of said tube, where it may be conveyed away by the cooling air current circulating around said tube.

Above the hollow upper extension 19 of the 35 spindle 14 there is provided a connecting pin 34 having an enlarged lower part 39 against which the upper end of coil spring 36 engages to urge the chisel edged upper end of the pin into penetrating engagement with the stranded wire 40 cable core 41.

As shown, the insulated cable 33 is adapted 45 to pass through a metal thimble or elbow 37, the latter having a flanged ring 38 soldered to its lower end and pivotable within the detachable coupling member 52 threaded on the end of the shielding element 10. Before attaching the thimble 37 the spacer tube 17 of Bakelite, or other rigid insulating construction, is inserted 50 to fit about electrode connection 34, with its skirt 18 telescoping with washer 28. The upper end of the tube 17 is flanged, as at 44, to rest upon asbestos disc 45 and overlie the upper edges of mica lining 16, and thus protect the mica lining 55 against fraying or bending out of position.

After passing the cable through the elbow thimble 37, a metal bracelet or collar 43 is pressed tightly about the rubber coating of the cable, at a point which is a pre-measured distance from the end of the cable. Coupling nut 52 and thimble 38, the latter being recessed to form an annular ledge 51 are then moved forward into the assembled relationship shown, wherein thimble 38 serves as a thrust bearing to prevent withdrawal of the cable so long as coupling member 52 remains in place as shown. When the member 52 is unscrewed from the shielding element 10 and drawn back (together with thimble 37, 38) along the cable, the latter may then be withdrawn and inspected, but spacer tube 17 will remain in place due to the fact that the spun-over end 61 of element 10 holds upper metallic washer 47 and flange 44 against displacement.

Preferably spacer tube 17 is grooved circumferentially, as indicated at 62, to facilitate heat dissipation and also to provide space for retention of a binding cement, if it is desired to apply such an auxiliary holding substance.

The insulator 20 of suitable ceramic material, such as porcelain, is positioned solidly within the shell by the action of threading parts 10 and 11 together. This action holds the insulator 20 against the shouldered portion 30 of the shell, a seal against escape or entry of fluid being effected at this point by the provision of the gasket 31 engaging the shoulder 30. Above this shoulder 30 the insulator may be peripherally grooved, and is also internally threaded as indicated at 33, the grooves being adapted to cooperate with the radial apertures 34 in the shell 11 to establish a path for the circulation of a cooling current of air, and the threads 33 being adapted to cooperate with corresponding threads on a metallic sleeve 35 of copper or other material having good heat conducting qualities, whereby a substantial amount of heat may be taken from the electrode 7 and spindle 14 and transferred through the insulator, to be dissipated along the surfaces of the grooves and through outlets 34. Heat not dissipated in this fashion may be transferred to the second region of air circulation around the heat radiating jacket 15, the heat flow path including parts 19, 28, 18 and 16.

Thus the spindle extension 19 which is riveted to the spindle, serves a double purpose: first, it keeps the spring 36 in place, and secondly, it tends to transfer a large measure of excess heat to the copper ferrule 28, for ultimate radiation by way of jacket 15.

In assembling the plug elements the first step is to braze or otherwise permanently weld the electrode spindle 14 within the metallic sleeve 35, and the second step is to apply a suitable cement to the threaded surfaces 33, so that upon threading the spindle carrying sleeve into the porcelain core 20 to the desired distance, the spindle will become securely bonded to the core 20 by virtue of the cement confined between the registering surfaces of the sleeve 35 and the bore 65 of the core 20. This cementing step, in conjunction with the gasket 31, renders the plug air and gas tight.

The outer electrode 8 is preferably made as a single piece, electrically or otherwise welded to the shell along the two cylindrical surfaces indicated at 5 and 6, between which surfaces there is a peripheral groove adapted to be filled by metallic ring 4 of a softer material such as copper having greater heat conductivity so as to facilitate the dissipation of excess heat which might other-

wise develop into grounded electrode 8. It will also be noted that although the normal path across which the high tension current will jump includes that portion of the electrode which is directly below the base of the central electrode 7, there is an auxiliary potential spark gap across to the inwardly extending circular ledge indicated at 3; but the primary purpose of this ledge 3 is to constitute a baffle to impede an entry into the interior of the plug of objectionable products of combustion.

To conform to standard practice, shell 11 will be made from suitable free-turning steel, while electrode 8 will be made from bendable metal having good spark resistant qualities, as, for example, a nickel-manganese alloy.

What I claim is:

1. In a spark plug of the self-shielding type, the combination with an insulating core of a center electrode carrying spindle secured within said core, a metallic shell surrounding said core and additional metallic means to facilitate heat transfer from said spindle to said shell, a cable receiving spacer tube fitting within the portion of said shell which extends above said core and a metallic skirt secured to said tube, said skirt and spacer tube constituting parts of the plug assembly, and remaining in place independently of the cable which is insertable therewithin.

2. A spark plug assembly including a shell, a core of preshaped material received within said shell, a central electrode carrying spindle within said core, and a mica lining for said shell, said mica lining being spaced from said core to allow room for circulation of heat convection currents therebetween.

3. A spark plug assembly comprising, in combination with a socketed shell for reception of an ignition cable, a central conducting spindle, a one-piece insulating core surrounding the central spindle and exposed at its base to the cylinder gases, and a resilient metal connection between said cable and said central conducting spindle, said resilient metal connection having contact with said spindle at a point substantially 45 below the upper end of said one-piece insulating core.

4. A spark plug assembly comprising, in combination with a socketed shell for reception of an ignition cable, a central conducting spindle, a one-piece insulating core surrounding the central spindle and exposed at its base to the cylinder gases, and a metal connection between said cable and said central conducting spindle, said metal connection having contact with said spindle at a point substantially below the upper end of said one-piece insulating core.

5. A spark plug assembly comprising, in combination with a socketed shell for reception of an ignition cable, a central conducting spindle, a one-piece insulating core surrounding the central spindle and exposed at its base to the cylinder gases, a resilient metal connection between said cable and said central conducting spindle, said resilient metal connection having contact with said spindle at a point substantially below the upper end of said one-piece insulating core, and a non-metallic spacer tube locked within said shell, to serve as the cable socket.

6. A spark plug assembly comprising, in combination with a socketed shell for reception of an ignition cable, a central conducting spindle, a one-piece insulating core surrounding the central spindle and exposed at its base to the cyl-

5 inder gases, a metal connection between said cable and said central conducting spindle, said metal connection having contact with said spindle at a point substantially below the upper end of said one-piece insulating core and a non-metallic spacer tube locked within said shell, to serve as the cable socket.

7. A spark plug assembly comprising, in combination with a socketed shell for reception of an 10 ignition cable, a central conducting spindle, a one-piece insulating core surrounding the central spindle and exposed at its base to the cylinder gases, a resilient metal connection between said cable and said central conducting spindle, 15 said resilient metal connection having contact with said spindle at a point substantially below the upper end of said one-piece insulating core, a non-metallic spacer tube locked within said shell, to serve as the cable socket, and a non- 20 metallic lining for that portion of said shell which lies between the base of the cable socket and the upper end of the one-piece insulating core.

8. A spark plug assembly comprising, in combination with a socketed shell for reception of an 25 ignition cable, a central conducting spindle, a one-piece insulating core surrounding the central spindle and exposed at its base to the cylinder gases, a metal connection between said 30 cable and said central conducting spindle, said metal connection having contact with said spindle at a point substantially below the upper end of said one-piece insulating core, a non-metallic spacer tube locked within said shell, to serve as 35 the cable socket, and a non-metallic lining for that portion of said shell which lies between the base of the cable socket and the upper end of the one-piece insulating core.

9. A spark plug assembly comprising, in combination with a socketed shell for reception of an 40 ignition cable, a central conducting spindle, a one-piece insulating core surrounding the central spindle and exposed at its base to the cylinder gases, a resilient metal connection between said 45 cable and said central conducting spindle, said resilient metal connection having contact with said spindle at a point substantially below the upper end of said one-piece insulating core, a non-metallic spacer tube locked within said shell, to serve as 50 the cable socket, and metallic means

telescopically connecting said insulating core and cable socket.

10. A spark plug assembly comprising, in combination with a socketed shell for reception of an 5 ignition cable, a central conducting spindle, a one-piece insulating core surrounding the central spindle and exposed at its base to the cylinder 10 gases, a metal connection between said cable and said central conducting spindle, said metal connection having contact with said spindle at a point substantially below the upper end of said one-piece insulating core, a non-metallic spacer tube locked within said shell, to serve as the cable socket, and metallic means telescopically connecting said insulating core and cable socket. 15

11. A spark plug assembly comprising, in combination with a socketed shell for reception of an ignition cable, a central conducting spindle, a one-piece insulating core surrounding the central spindle and exposed at its base to the cylinder 20 gases, a resilient metal connection between said cable and said central conducting spindle, said resilient metal connection having contact with said spindle at a point substantially below the upper end of said one-piece insulating core, 25 a non-metallic spacer tube locked within said shell, to serve as the cable socket, a non-metallic lining for that portion of said shell which lies between the base of the cable socket and the upper end of the one-piece insulating core, and metallic 30 means telescopically connecting said insulating core and cable socket.

12. A spark plug assembly comprising, in combination with a socketed shell for reception of an 35 ignition cable, a central conducting spindle, a one-piece insulating core surrounding the central spindle and exposed at its base to the cylinder gases, a metal connection between said 40 cable and said central conducting spindle, said metal connection having contact with said spindle at a point substantially below the upper end of said one-piece insulating core, a non-metallic spacer tube locked within said shell, to serve as the cable socket, a non-metallic lining for that 45 portion of said shell which lies between the base of the cable socket and the upper end of the one-piece insulating core, and metallic means telescopically connecting said insulating core and cable socket. 50

EDWARD B. NOWOSIELSKI. 60
